SHIRT

Herman J. Tillery, 1247 E. 105th St., Cleveland, Ohio

Filed July 23, 1962, Ser. No. 71,026

Term of patent 7 years

(Cl. D3—25)

The figure on the drawing is a front view of a shirt showing my new design; the shirt is shown folded back for convenience of illustration. The back of the shirt is conventional in appearance as are the sleeves and the folded under portions.

The characteristic feature of my design resides in the combination on the shirt disclosed of the contrasting eyelets on the collar in association with the special lacing therethrough, substantially as shown.

I claim:

The ornamental design for a shirt, as shown and described.
